LOCK HANDLE ASSEMBLY

Samuel Bartlett McKenzie, Toronto, Ontario, Canada, assignor to Connector Locks (America), Inc., Detroit, Mich., a corporation of Delaware

Application August 22, 1945, Serial No. 612,048

3 Claims. (Cl. 292—348)

1

The present invention relates to improved lock handle assemblies.

Pursuant to the instant invention, the lock handle assembly comprises the combination of resilient means such as a coil spring assembly functioning with complementary camming elements whereby resiliency is imparted to the movement of operating the handle and the lock or other connector means.

In preferred embodiments of the invention, such resilient means functions also to safeguard against tampering by unskilled persons with the lock parts and particularly in regard to the pin or equivalent serving to retain the handle assembly in operative status.

In the most preferred forms of the invention, the retaining pin possesses a formation co-ordinated with pin-receiving slots of predetermined dimension provided in the spindle of the assembly, whereby maintenance of the lock handle assembly is assured against tampering by unskilled persons, but removable by a skilled mechanic in the circumstances requiring the disassembly of the lock.

More specifically, the invention comprises in combination with a lock or other connector mechanism per se and a square or other polygonally configurated spindle, of a handle resiliently connected with one end of such spindle, the opposite end of the spindle being provided with pin-receiving slots of predetermined longitudinal dimension, and a retaining pin having relatively large and small parts, the relatively small part of the pin being received within the stated pin-receiving slots of the spindle, the relatively large part or parts of the pin serving to lock the retaining pin in mechanical connection with the spindle of the nature reasonably proof against tampering by an unskilled person, but disconnectable by a skilled person.

In preferred embodiments of the invention, the coil spring or equivalent resilient means is enclosed in a cylindrical sleeve which may be connected with the knob either integrally or otherwise fixedly in combination with the connection of the spindle of the lock with the knob either by means of a cam follower associated with a pin passing through the spindle or by means of a lost motion connection between the spindle and the knob, such cylindrical sleeve bearing within

5 the cylindrical opening in the rose, whereby a free and easy working of the handle is attained in the movements of operating the lock. Such free and easy working characteristic of the connection of the knob with the spindle serves also to compensate for any misalignment of the assembly of the handle per se and the lock per se, and also any inaccuracy in drilling of openings in the door in the installation of the door lock.

10 The stated advantages are attained independently of the above referred to or other specific form of pin-connection of the knob or other handle with respect to the spindle, for safeguarding against tampering.

15 Further features and objects of the invention will be more fully understood from the following detailed description and the accompanying drawings, in which:

Fig. 1 is an elevational view of a preferred embodiment of the improved door handle assembly, partly broken away in horizontal central section to expose otherwise hidden parts. This view shows the parts in normal, i. e., unturned position.

20 Fig. 2 is a view similar to that of Fig. 1 but showing one handle and the spindle and associated parts displaced toward the right as viewed in the figure.

Fig. 3 is a fragmentary exploded perspective view of a cam-provided rose and therewith co-operating cam follower sleeve.

25 Fig. 4 is a fragmentary perspective view of the assembly of the spindle and one of the handles.

Fig. 5 is a detail sectional view on line 5—5 of Fig. 4.

30 Fig. 6 is a central vertical sectional view of another embodiment of the invention.

Fig. 7 is a central vertical sectional view of another embodiment of the invention.

Fig. 8 is a central vertical sectional view of another embodiment of the invention.

Referring to the preferred embodiments of the invention illustrated in the drawings, the improved door handle assembly comprises the rotatable operative spindle 10 which is arranged to be passed through a perforation 11 in a door 12, and is associated with a lock indicated generally at 13 of conventional or other approved type.

The roses 14, 15, shown at the opposite faces

2

of the door, may have any desired exterior configuration for ornamentation, but for the purposes of the present invention each includes a hollow formation 16 which is received in the recesses 17, 17, formed at the opposite faces of the door, the stated perforation 11 passing centrally through such recesses 17, 17. Such recesses may have a circular cross sectional configuration.

As shown in Figs. 1 and 2, the door handle assembly may include a knob 18 of conventional or other approved type at one side of the door and a handle 19 or operating member of rectilinear configuration at the opposite side of the door. It is desirable that the rectilinear handle 19 when in neutral position extend in a horizontal plane. A rectilinearly extending handle may be employed also in lieu of the conventional circular knob 18 at the opposite side of the door.

In each instance, the knob or rectilinearly extending handle comprises a cylindrical sleeve, the sleeve of the knob-type of handle being designated 20 and the sleeve of the rectilinearly extending handle 19 being designated 21.

As shown in Figs. 1 and 2, the spindle 10 is assembled with the knob 18 through the intermediary of a cam sleeve 22 which has at its one side diametrically disposed V-shaped notches 23, 23 and is connected at its opposite side to the knob 18, as by forming its face 24 convergently tapered to conform to the like tapered frusto-conical face 25 of the knob part 18b and providing on the face 24 oppositely disposed spline-like projections 24a, 24a received within slots 18c, 18c formed in the knob face 25, see Fig. 4. Such cam sleeve 22 co-acts with the pin 26 carried by or inserted in the spindle 10, whereby the spindle 10 is secured relative to the body of the knob 18. To effect such assembly, the knob 18 is formed, as indicated above, of complementary parts, 18a, 18b affording when disassembled access to the stated cam sleeve and its pin and to the spindle.

The stated knob assembly comprises further the cam sleeve follower 27, which is located within the knob sleeve 20 and has an outer circular periphery slightly less than the inner circular periphery of the sleeve 20. The cam sleeve follower has a central square bore 27a conforming to that of the spindle 10 which passes therethrough, see Fig. 3. The outward face 27b of the cam sleeve follower is flat, against which one end of the expansile coil spring 28 abuts; the opposite end of such spring abuts against the flat face 20a at the junction of the sleeve 20 with the body of the knob. The cam sleeve follower 27 is provided at its inward face with camming peaks 29 which cooperate with the oppositely disposed cam elements 30, 30, formed at the inner face of the base formation 16 of the rose 14; these cam elements 30, 30, are symmetrically disposed with respect to the bore 16a of the base 16.

The stated component parts at one side of the door are assembled by threading the spring 28 and then the cam follower sleeve about the free end of the spindle 10, which is thereafter inserted through the opening 16a of the hollow base 16 of the rose 14, then through the hole in the door and the operating opening of the selected lock 13; the free end of the spindle is now inserted through the opening 16b of the cylindrical base 16 of the rose 15.

Adjacent the free end of the spindle 10 are formed open transverse slots 31 for the reception of a retaining pin 32 which is of special construction. As shown in Figs. 1 and 2, such pin 32 is of general I-shape, that is to say, having a central

portion which is greatly reduced as compared with its opposite end portions, the central portion being disposed substantially symmetrically with the opposite end portions. Co-ordinated with such retaining pin 32, the slots 31 each has a dimension longitudinally of the spindle 10 but slightly greater than the corresponding dimension of the larger end portions of the pin 32, for the purposes presently explained. Further associated with such pin and slotted spindle assembly is the collar 33 having a square bore 33a corresponding to the outer periphery of the body of the spindle 10 and a transverse bore 33b corresponding to and but slightly larger than the peripheral configuration of the larger end portions of the pin 32.

The completion of the assembly of the stated parts may be more readily explained by reference to Fig. 2, which illustrates the knob handle sub-assembly having been pressed in the direction toward the door 12 as indicated by the arrow 34, thereby compressing the spring 28, and whereby the free end of the spindle 10 is projected in the direction of the arrow 34. In such position, the free end of the spindle is inserted within the open end of the sleeve 21 of the handle 19, then through the bore 33a of the collar 33, the collar being shifted to locate its transverse bore 33b in alignment with the registering openings 35 of the sleeve of the handle 19, to enable the retaining pin 32 to be inserted through one of such registering openings 35, thence through the forepart of the bore 33b of the sleeve 33 and the selected slot 31 of the spindle 10, then through the postpart of the bore 33b and finally into the opposite opening 35 of the handle sleeve.

Upon releasing the pressure on the knob 18, the expansile spring 28 returns the knob and the spindle and the stated therewith associated parts in direction opposite to that of the arrow 34. In such return movement the assembly of the pin 32, its collar 33, the registering openings 35, 35, of the handle sleeve 21 are brought inwardly of the rose 15, whereupon the handle assembly is in its normal relation.

It is observed that the rose 14 is shown provided with points 36, 36, etc. for affording forcible insertion into the wood or other material of the door 12, thus insuring permanence of positioning of its cam elements 30, 30. A similar manner of securing is provided for the rose 15.

Such return movement effects the important change of relationship of the pin 32 with respect to the slot 31 of the spindle through which the pin has been inserted, namely that the shoulders between the larger end portions and the smaller central portion of the pin 32 are brought into engagement with the body of the spindle adjacent the edges of the selected slot 31 of the spindle, thereby locking the pin 32 with respect to the spindle. By such arrangement, the pin 32 is precluded from accidentally dropping out of connection with the spindle. It will be observed that such secured locking of the pin 32 with respect to the spindle is maintained in the circumstance that the knob 18 be pressed toward the door, in which circumstance the opposite shoulders of the pin 32 engage the body of the spindle adjacent the opposite edges of the selected slot 31 of the spindle.

The above arrangement, it will now be apparent, precludes the possibility of children or other unskilled persons from tampering with the lock handle in the effort to disconnect the pin 32 from the lock handle and thus disassemble the lock

handle. However, an expert by experience is able to disconnect the pin 32 by carefully shifting the spindle 10 to locate the slot 31 in which the pin has been inserted to position its side faces in substantial alignment with the side faces of the larger end portions of the pin, and then tampering the pin to remove the same.

It is desirable to install and normally position the rectilinear handle 19 of the lock handle in horizontal position, which objective is attained by securing the rose 14 of the handle assembly to locate its cam elements 30, 30, in the vertical plane, as shown in Fig. 1, whereby through the mediation of the cam follower sleeve 27 and the spindle 10, and the assembly of the collar 33, pin 32 and the sleeve 21, the rectilinearly extending handle 19 assumes a horizontal position, and is restored to such horizontal position after release when turned to operate the lock.

If preferred, a rectilinearly extending handle, similar to the stated handle 19, may be substituted for the knob type of handle 18, the securing of the inner end of the spindle with respect to such rectilinearly extending handle being carried out similarly as illustrated and described with respect to the knob handle 18, that is to say, to provide a sleeve such as the sleeve 20, camming sleeve 25, frusto-conically associated with such sleeve 20 and a pin 26 functioning with the camming end of such sleeve 25.

From the above it is apparent that the invention comprises a lock handle sub-assembly inclusive of a sleeve secured to a handle, whether of the knob type or of the rectilinearly extending type, a cam collar and a pin therefor, in combination with an expansile spring, a cam sleeve follower having cam peaks in cooperation with camming means affords resilient action in the movement of turning the handle to operate the lock or other connector, the stated camming means functioning to increase the leverage of the force applied to the handle as the turning movement is continued. Such resiliency-provided movement pertains also in the operation of the opposite handle, since the turning motion of the spindle is identical, irrespective of the end of the spindle to which the turning force is applied.

The biasing, and preferably resilient, means of the handle assembly afforded by the expansile spring 28 functions to afford an easy movement in the operation of the lock or connector, as well as to normally maintain the retaining pin 32 in its locking relation of the operating parts of the assembly.

In the embodiment shown in Fig. 6, the knob 18 is formed of complementary parts 18a, 18b similarly as in the preceding embodiment; in the Fig. 6 embodiment the cam sleeve 22 is cast or otherwise formed integrally with the knob part 18b and also with the cylindrical sleeve 20.

In the Fig. 7 embodiment of the invention, the cam sleeve 22 is integrally connected with the cylindrical sleeve 20; in this construction, the knob 18 is of hollow formation, either integral or of component parts, and has a circular opening indicated at 37 at its inward side, the defining face of such opening 37 being provided with suitable disconnecting means such as threading mating with the threading formed at the outer circular periphery 22a of the cam sleeve 22.

In the construction of the embodiment illustrated in Fig. 8, the knob 38 is integrally or otherwise fixedly secured to the cylindrical sleeve 20; within the body of the knob is formed the recess 39 into which the end 10a of the spindle 10 pro-

jects. The perforation 10b is formed in the end portion 10a of the spindle through which projects the pin 40, for connecting the knob to the spindle 10. Such spindle extends through the perforation 41 formed in the body of the knob 38. As shown, such connection of the knob with the spindle may have a limited lost motion, afforded by the relatively enlarged dimensions of the recess 39 with respect to the dimensions of the pin 40 and the curved formation of the bottom of the recess 39, and corresponding curved tip of the end portion 10a of the spindle. Such knob 38 may be unitary, or may be formed of component parts 38a, 38b, as shown, and connected together as a unit by the provision of the ring 42 screw-threadedly or otherwise disconnectably connecting such component knob parts.

The parts of the embodiment illustrated in Figs. 6, 7 and 8, in common with those of the embodiment shown in Figs. 1 through 5, are designated by like reference characters.

Pursuant to the embodiment typified by the several constructions illustrated in Figs. 6, 7 and 8, the lock handle may be provided with any desired type of configuration of the knob or handle or other form of manually operating member.

I claim:

1. In a lock handle assembly including a spindle and handles secured at the respective opposite ends of the spindle, the combination of a pin-receiving opening adjacent an end of the spindle; a sleeve disposed at such end portion of the spindle, said sleeve being provided with oppositely disposed mutually registering openings; a pin having shoulders formed by oppositely disposed end portions of relatively large dimension in the direction longitudinally of the spindle and a central portion of relatively reduced dimension in the stated direction, the dimension of each pin-receiving opening in the longitudinal direction of the spindle exceeding that of said larger end portions of the pin; and means for biasing the spindle in the direction of its length whereby the pin is held in its receiving openings by engagement of its shoulders with the body of the spindle.

2. The combination as defined by claim 1 in which the pin-receiving opening is a slot open laterally of the spindle.

3. In a lock handle assembly including a spindle and handles secured at the respective opposite ends of the spindle, the combination of a pin-receiving opening adjacent one end of the spindle; a sleeve disposed at such end portion of the spindle, said sleeve being provided with oppositely disposed mutually registering openings; a pin having an intermediate portion which is slender relative to its opposite end portions, the said end portions of the pin being formed to substantially mate with the respective openings in said sleeve, and the said slender intermediate portion of the pin being formed to substantially register with said pin-receiving opening of the spindle, the said pin-receiving opening of the spindle conforming in shape with and being not less in cross-sectional dimension than the said openings in the sleeve, said pin being disposed with its said end portions mating with the respective openings in the sleeve and its said slender intermediate portion extending through the pin-receiving opening of the spindle; and means normally biasing the spindle in the direction of its length, whereby the pin is locked in its receiving openings by engagement of its said end portions with the spindle.

SAMUEL BARTLETT McKENZIE.
